UNITED STATES PATENT OFFICE

2,339,925

SUSPENSION BRIDGE

Wilhelm Haupt, Dortmund-Hoerde, Germany;
vested in the Alien Property CustodianApplication September 2, 1938, Serial No. 228,204
In Germany September 24, 1937

1 Claim. (Cl. 14—18)

In patent application Serial No. 126,471, of February 18, 1937, protection is claimed for bridge supporting structures which in the space between two roadways have a torsion-resisting foot projecting beyond these roadways and which is capable by its torsional strength of taking up the overturning moments imparted by one-sided traffic load. In this patent application a supporting structure for suspension bridges is described, in which the torsion-resisting foot is formed by a torsion-proof stiffening supporting structure. It is absolutely essential, that the stiffening supporting structure is made proof against torsion because the overturning moments occurring in the case of one-sided traffic loading would not otherwise be taken up.

In the suspension bridges hitherto generally known with at least two suspension rod supporting walls between which the main track is arranged, a torsion-proof construction of the stiffening supporting structure is not essential because, in the case of one-sided traffic loading, one of the suspension rod supporting walls is merely loaded slightly more than the other suspension rod supporting wall, with the result that the overturning moment is taken up.

However, in this mode of construction the objectionable fact became apparent that the roadway under one-sided traffic loading inclines to a considerable extent in the transverse direction, this transverse inclination attaining under certain circumstances for example the value of 1:30 or even more. It is obvious that such a steep transverse inclination means very great technical disadvantages for high speed traffic, for example high speed electric railways and the like. The extent of this transverse inclination can be considerably reduced if the stiffening supporting structure is made proof against torsion. It is known, that the deformations of a torsion-proof hollow body are exceptionally slight as compared with the saggings of a cable. Therefore, by the torsion-proof construction of the stiffening supporting structure it is possible to attain a transverse inclination of the bridge under one-sided traffic load of only a fraction of the value which occurs when the stiffening supporting structure is not made proof against torsion. The greater the torsional strength of the stiffening supporting structure is made, the more will the one-sided traffic load be relieved on the nearest suspension rods supporting wall and the opposite suspension rods supporting wall is utilized for taking up the vertical load. In the optimum case the stiffening supporting structure can be made of such

great torsional strength that, if one supporting cable is entirely destroyed, it takes up entirely the strong overturning moments then produced by the continual load. The advantage is enormous, especially in case of war, as, even in the event of a whole cable being destroyed, the bridge does not collapse (with the result that under certain circumstance the road running under the bridge might also be blocked), but is still capable of allowing traffic even if on a restricted scale.

The torsional strength of the stiffening supporting structure can be attained in various ways, for example:

(1) By connecting the upper and lower flanges of each of two vertical stiffening girders by a horizontal connection, it being evident that such a horizontal connection may consist of a solid plate or of a stiff roadway plate,

(2) Where the stiffening supporting structure consists of a three-flange girder or of a tube. As it is known, that the tube cross-section is the most favorable cross-section for taking up torsional stresses, the diameter of this tube can be relatively small and the tube itself can, if desired, be used directly as conduit for gas, water or other fluid.

The advantages of a torsion-proof stiffening supporting structure may be ensured even for a supporting structure partly destroyed by bombs, if instead of two vertical stiffening girders more than two such girders are arranged whose upper and lower ribs are connected by horizontal connections. If in such a stiffening supporting structure one or several stiffening girders are destroyed by bombs the remaining girders remain torsion-proof with their horizontal connections and are still capable of reducing to an appreciable extent the transverse inclination of the roadway under one-sided traffic loading.

Referring to the drawing for a more complete disclosure:

Fig. 1 is a diagrammatic transverse view and Fig. 2 is a diagrammatic longitudinal view of a suspension bridge embodying my invention.

The bridge is suspended from two supporting cables 1 by means of rods or cables 2. The stiffening supporting structure below the roadway or track 3 is formed by the vertical transverse stiffening girders 4, arranged at various distances apart and may be constructed as plate girders or as framework girders. On each side of the main track 3 a footway or auxiliary roadway 5 may be provided.

The torsion proof stiffening supporting structure comprises a torsion-proof tube 6 to which

the transverse girders 4 are rigidly secured, the supporting structure being in turn rigidly connected with the abutments 7. The tube 6 is located substantially in the center of the bridge and extends longitudinally the entire length of the bridge.

I claim:

In a suspension bridge having at least two rows of suspension rods, a main roadway arranged between said rows of suspension rods, and a torsion-proof stiffening supporting structure

below said roadway rigidly connected with the abutments against twisting for taking up the tilting moments occasioned by one-sided loadings on said roadway, said torsion-proof structure comprising a tubular member substantially in the center of said bridge and extending longitudinally for the entire length of the latter, and a series of transverse girders rigidly secured to said tubular member.
